UNITED STATES PATENT OFFICE.

JOHN BURRY, OF RIDGEFIELD PARK, NEW JERSEY.

PAPER-FEEDING MECHANISM.

SPECIFICATION forming part of Letters Patent No. 734,297, dated July 21, 1903.

Original application filed April 13, 1900, Serial No. 12,660. Divided and this application filed July 17, 1901. Serial No. 68,649.
(No model.)

To all whom it may concern:

Be it known that I, JOHN BURRY, a citizen of the United States, and a resident of Ridgefield Park, in the county of Bergen and State of New Jersey, have invented a certain new and useful Improvement in Paper-Feeding Mechanism, of which the following is a specification.

This application is a division of my prior application for Letters Patent of the United States, filed April 13, 1900, Serial No. 12,660, now Letters Patent numbered 680,693, dated August 20, 1901.

The present invention relates to mechanism for feeding paper in a step-by-step manner in an automatic manner in printing-telegraph and like machines.

One object of this invention is to feed paper from a roll in a step-by-step manner by escapement-controlled power-driven mechanism.

Another object is to store power automatically for operating such feeding mechanism.

Yet another object is to avoid damage to an actuating-spring for such mechanism.

Another object is to secure substantially uniform line-spacing when the escapement is connected directly with the spool on which a web of paper is wound.

Other objects will appear hereinafter.

To these ends the invention consists of features of construction and combinations of devices hereinafter described, and more particularly pointed out in the appended claims.

One form of the invention is illustrated in the accompanying drawings, forming part of this specification, in which—

Figure 1 is an end view, with parts omitted, of a machine in which the invention is embodied. Fig. 2 is a plan of the same, certain parts not essential to an understanding of the present invention being omitted for the sake of clearness. Fig. 3 is a view, partly in vertical section, of mechanism shown in the preceding figures. Fig. 4 is a horizontal plan, partly in section, of the same. Fig. 5 is a detail view of spring-winding mechanism. Fig. 6 is a view showing certain positions of certain parts. Fig. 7 is a like view showing said parts in other positions. Fig. 8 is a detail view of a mounting for the bobbin or spool. Fig. 9 is a detail view in

section of an arm and a sliding pawl-carrier thereon. Fig. 10 is a detail view on a scale larger than that of the previous figures, illustrating the variable escapement. Fig. 11 is a rear view, on the scale of Fig. 10, of the same; and Fig. 12 is a plan, on the same scale as Fig. 10, of the same mechanism.

The framework comprises a base-plate *a*, three vertical plates *b c d*, secured to base *a*, and tie-rods and plates joining plates *b c d* together.

The paper used in the apparatus shown in the drawings is in the form of a web wound to form a roll, the web being several inches wide and the writing being done transversely of the web. The web 1 is wound on a wooden bobbin or cylinder 2, which is bored through longitudinally to receive a shaft 3, by which the roll is supported in the machine. At one end the shaft 3 sets into a socket in a shaft 4 of a large ratchet-wheel 5 and at its other end is held in an open bearing in a pivoted spring-arm 6. A collar 7 on the shaft 3 prevents said shaft from sliding out of the bobbin as long as the arm 6 engages with the end of the shaft. The arm 6 is held up by a tooth 8, which is oblique or slanting on one side to cause a wedging-off action on the arm 6 as the latter is lifted into position for holding the shaft 3. The web 1 passes from the under side of the roll up in front of a platen *p*, against which it bears, and thence upward and backward between feed-wheels 9 and pressure-rolls 10.

The wheels 9 are loosely mounted upon a shaft 11, which is journaled in a lug on top of plate *d*, and in a detachable bearing 12 on the plate *b*. The shaft 11 is provided with two circumferential grooves 13, and the hubs of the wheels 9 have screws 14, which engage with threaded holes therein and which extend into said grooves 13, thus permitting the wheels 9 to move circumferentially but not to move longitudinally of the shaft 11. The hub of each wheel 9 is also provided with a circumferential groove 15, arranged to receive one end of a coiled wire spring 16, Fig. 2, there being a spring 16 for each wheel 9. About its middle the shaft 11 is provided with two circumferential grooves 17, Fig. 5, for receiving the other ends of said springs 16. The springs 16 grip the hubs of the

wheels 9, but do not touch the shaft 11 until near the grooves 17, where they grip the shaft and have their ends resting in the grooves 17. The springs 16 are wound in reverse directions, and each is by preference set to have its coils increased in diameter as the spring is put under more tension, as hereinafter set forth, so that when said tension reaches a certain maximum the ends of the springs slip 10 on the shaft 11 and overwinding of the springs is prevented.

The means shown in the drawings for putting the springs under tension comprise a worm-wheel 18, loose on the shaft 11, a worm 19, meshing with wheel 18, Fig. 3, a ratchet-wheel 20, fast on shaft 11, a pawl 21, pivoted on worm-wheel 18, a spring 22, fast to wheel 18 and bearing on pawl 21 to press it into engagement with the ratchet 20, a ratchet-wheel 23, fast on the shaft 24 of the worm 19, and a spring arm or pawl 25, fast on the shaft 26 and coacting with the ratchet 23. The shaft 24 is journaled in lugs or ears on or detachably connected to the plate d, Fig. 3, and 25 there is a fly-wheel 27 fast to said shaft 24, the fly-wheel acting to continue the winding action by continuing the motion of the shaft 24 after the pawl 25 ceases to turn it. The worm 19 turns the worm-wheel 18, and 30 the motion is communicated to the shaft 11 through the described connections between the shaft 11 and the worm-wheel 18. The shaft 11 puts the springs 16 under tension when turned by said devices.

35 The pressure-rolls 10 are rotatably mounted in forked arms 28, Fig. 2, and these are pivoted at 29 in lugs or ears 30, fast to the plates b d. Each arm 28 is formed with an angular part or corner 31, against which springs 32 bear to hold the rolls 10 against wheels 9 or away from them, according to which side of the corners 31 the said springs bear. The springs 32 are fast at one end to the ears 30. The rolls 10 are faced with soft rubber on 45 their peripheries and coact with the toothed peripheries of the said wheels 9, thus giving the feeding devices a good grip upon the web 1 near the edges thereof.

50 The shaft 11 has a disk 33 fast thereto between the said grooves 17, said disk being equal in diameter to the wheels 9 and supporting the web 1 at a point intermediate the feed-wheels. The shaft 11 also has a hand-wheel 34 fast thereto at a point overlying the 55 plate b, which plate is recessed to provide room therefor. The hand-wheel 34 is used for putting the springs 16 under tension when a fresh roll of paper is put in the apparatus, as the springs 16 run down of themselves as soon as the resistance due to the letting-off mechanism ceases.

55 The springs 16 are wound continually during the operation of the entire apparatus (as more fully set forth in said prior application) and tend to turn the wheels 9, and so to draw the web 1 forward. The web is held against forward motion and is released from time to

time by automatically - acting mechanism such as that shown in the drawings and now to be described.

70 The bobbin 2 has a pin 35 projecting from that end thereof which comes against the wheel 5, said pin projecting between two of the spokes of said wheel and turning the wheel when the said springs 16 are allowed 75 to draw the paper between the wheels 9 and rolls 10, and said wheel 5 is released for that purpose. The wheel 5 is prevented from turning under the pull of the springs 16 and the web 1 by a detent 36, Fig. 3, which engages 80 with the wheel. The detent 36 is fast on a shaft 37, which is journaled in the plates c d. The shaft 37 is provided with an arm 38 thereon outside of the plate c. A spring 39 bears against said arm 38 in such wise that 85 the shaft 37 is turned to keep the detent 36 in engagement with the wheel 5. The spring 39, Fig. 2, is fast at one end to the arm 38 and at its free end bears in a groove in a pin 40, projecting from the plate c.

90 The ratchet-wheel 5 and the detent 36 form part of an escapement mechanism by means of which the web 1 is permitted to be unwound from the roll by the pull exerted thereon by the springs 16. A lever 41, Fig. 95 3, is pivoted or fulcrumed intermediate its ends on a pin 42, projecting from the side of plate d, and it is connected with the detent 36 by a link or rod 43, which is pivotally connected with both detent and lever. 100 The rear end of the lever 41 has an arm 44 pivoted thereto by a pin 45. A spring 46, fastened to lever 41 and hooked to the arm 44, acts to move the arm in a plane parallel to the plane of the wheel 5 and away from the 105 detent 36. A stop-screw 47, adjustable in a standard 48, rising from the base a, serves to limit the rearward motion of the arm 44 under the influence of the said spring 46. The arm 44 has a parallel-sided through-slot, Fig. 110 4, extending from its lower end vertically, and a pawl-carrier 50, I-shaped in section, is guided in said groove or slot and is held up by a spring 51, which connects the carrier and the arm 44 and draws the carrier 50 to 115 the upper extreme of its motion. The working tooth 52 on the carrier 50 is normally out of engagement with the teeth of the wheel 5, as shown in Fig. 3. Whenever the shaft 37 is moved against the force of spring 39, the 120 detent 36 is moved down out of engagement with the wheel 5 and through the link 43, lever 41, arm 44, spring 51, and carrier draws the pawl 52 up into engagement with the teeth of the wheel 5. The spring 51 allows 125 of the disengagement of the detent 36 from the wheel 5 after the pawl 52 is in position to engage with or has engaged with a tooth of the wheel 5. As soon as the detent 36 is out of engagement with the wheel 5 the web 1 is drawn upward by the action of the springs 16 until the arm 44 is arrested in some manner.

Inasmuch as the roll decreases in size as the paper is drawn therefrom, it is requi-

site that the pawl 52 have a variable throw in order that the lines of writing may be uniformly spaced upon the paper.

According to the present invention the devices for governing the motion of the pawl 52 circumferentially of the said wheel 5 to cause the pawl to have a variable throw are themselves controlled in their action by the roll of paper, so that as the diameter of the roll decreases the throw of the pawl increases. In the instance shown in the drawings the said throw of the pawl 52 is controlled by a slide 53, which has an arm 54, adapted to rest on top of the roll of paper, and a stop-arm 55, adapted to coact with the arm 44 to limit the motion thereof toward the detent 36 as the paper is drawn from the roll by said springs 16 and the mechanism operated thereby. The slide 53 moves in a vertical groove 56 in the side of the plate *d*, being held in place by bars 57, secured by screws to plate *d*. The slide 53 and its stop-arm 55 move in a direct vertical line, while that surface of arm 44 which coacts therewith is straight, but is inclined to the vertical and gets farther and farther away from the guideway 56 toward the bottom of the machine, said pawl 52 being at the under side of the wheel 5. From this arrangement of parts it results that as the stop 55 moves down the arm 44 has more and more throw before it is arrested by the stop 55, so that the decreasing diameter of the roll of paper does not result in the crowding together of the lines. On the contrary, the lines are at substantially uniform distances apart, the slight error introduced by giving the stop 55 a straight course and the back of the arm 44 (that coacting with the stop 55) a straight edge not being perceptible, or at least not causing any disadvantageous crowding together of the lines. The motion downwardly of the stop 55 is governed by the diameter of the roll of paper, since the arm 54 rests on the roll directly over the axis thereof and follows the roll as the diameter thereof decreases, so that as the roll decreases in size the pawl 52 has more and more throw before it is arrested by the stop 55.

The references 58 59 indicate two electro-magnets, which in the printing-telegraph instrument wherein the present invention has been used are in different circuits controlled by the same set of keys, there being one key for each letter or character printed.

60 is an electromagnet, the circuit through which is controlled by said magnets 58 59, as in said prior application is more fully set forth.

61 designates the armature for magnets 58, 60 and 62 a shaft to which said armature 61 and lever 63 are fast.

64 is a spring for drawing lever 63 against stop 65 and armature 61 away from magnet 58.

65 66 is a spring-arm fast to lever 63 and adapted to engage behind a stop 67.

68 is the armature of magnet 59, and 69

is a bell-lever fast to same shaft as armature 68.

70 is a stop for lever 69. The lower end of 70 the lever 69 has a catch 71 pivoted thereto, said catch having two pins 72 projecting therefrom, between which the arm 66 passes.

73 is the armature of magnet 60, and 74 is a shaft to which armature 73 and lever 75 are 75 fast, and 76 is an extension of lever 75. The extension 76 is adapted to cam the oblique end of spring-arm 66 from engagement behind stop 67, whereby the arm 66 is permitted to throw the catch 71 from the position 80 thereof shown in Fig. 1 to the position thereof shown in Figs. 6 and 7.

77 is a stop for lever 75, and 70^x and 73^x are returning-springs for levers 69 and 75. Armature 68 and lever 69 are fast upon the 85 shaft 26, above mentioned, to which shaft the pawl 25 is also fast.

In the machine in which the present invention has hitherto been used the magnets 58 59 are energized every time a key is depressed, the circuits being so arranged that magnet 58 is energized before magnet 59 is. The energizing of magnet 58 draws down armature 61, raises lever 63, and puts spring-arm 66 under tension, said spring-arm 66 being caught at this time behind stop 67, as shown in Figs. 1 and 2. The later energizing of the magnet 59 draws its armature to the left in Fig. 1, and this moves lever 69, thus carrying the catch 71 to the left in Fig. 100 1 above the rabbeted end of the arm 38. As set forth in said prior application, the circuit through magnet 60 is controlled by the magnets 58 59, whence it follows that the lever 75 is not lifted until after lever 69 has 105 been moved, as above stated, whereby the release of the arm 66 from stop 67 by the arm 76 follows the passage above the end of arm 38 of the catch 71; but the drawing of armature 68 by magnet 59 causes the pawl 25 to 110 rotate the ratchet 23 and shaft 24, thus causing the worm 19 to rotate the worm-gear 18 and shaft 11 and wind the springs 16 somewhat, the fly-wheel 27 continuing the winding of said springs for a time after pawl 25 115 ceases to rotate the shaft 24. During the above-described operations the detent 36 holds ratchet-wheel 5 from turning under the pull on the bobbin by the weband springs 16. 120

When it is desired to feed the paper forward for a new line, the operation follows the printing of a character by the following sequence of operations: As above stated, printing occurs every time the magnets 58 59 are energized in that order by the closing or shunting of a circuit through the magnet 60. The magnets 58 59 are in independent circuits, and if these two circuits are broken simultaneously after the printing of a letter no line-feed of the paper takes 130 place. If, however, the proper one of said circuits be broken and then remade after such printing while the other circuit remains unbroken, then such line-feed does take

place. Thus, after a letter has been printed and before the key is released the circuit through the magnet 59 is broken, whereupon armature 68 and lever 69 resume the positions thereof shown in Fig. 6, and this breaks the circuit through the magnet 60, and its armature thereupon returns to the position thereof shown in Fig. 6. The return of lever 69 to normal position (see Fig. 6) 5 draws the catch 71 back over the end of arm 38 until the spring-arm 66 throws the catch 71 into engagement with the rabbeted end of the arm 38, as shown in Fig. 6. The circuit through magnet 59 is now made again, 10 whereupon the armature 68 and lever 69 are drawn to the positions thereof shown in Fig. 7, and catch 71 moves the lever or arm 38 to the position thereof shown in Fig. 7, thus giving shaft 37 a partial turn. This partial 15 turn of the shaft 37 is sufficient to move detent 36 out of engagement with the wheel 5 and to draw pawl 52 up into engagement with said wheel, whereupon the springs 16 rotate the shaft 11 and feed-wheels 9 10 and 20 draw the web 1 from the roll until arm 44 is arrested by the stop 55. Upon releasing the 25 depressed keys (or key) the circuits through magnets 58, 59, and 60 are broken, and the springs 39, 64, 70^X, 46, and 73^X restore the 30 parts to the positions thereof shown in Figs. 1, 2, and 3.

The invention is susceptible of embodiment in forms other than that shown in the drawings and hereinbefore described. I do not 35 therefore restrict this specification and claims to the precise form above described.

What I claim as new, and desire to secure by Letters Patent of the United States, is—

1. The combination of a roll of paper, a roll-holder, a spring-actuated feed device for drawing the paper from said roll, and variable escapement mechanism for controlling the rotation of said holder, substantially as described.

2. The combination of a roll of paper, spring-operated means for unwinding said paper from said roll, and a variable escapement mechanism for controlling the action of said spring means, substantially as described.

3. The combination of a roll of paper, a feed-wheel, a presser coacting with said wheel to feed the paper from said roll, a spring for rotating said wheel, and electromagnetically-operated means for winding said spring, with 55 escapement mechanism for governing the rotation of said roll, substantially as described.

4. The combination of a roll of paper, a feed-wheel, a presser coacting with said wheel to feed the paper from said roll, a spring for rotating said wheel, electromagnetically-operated means for winding said spring, and escapement-controlled roll-holding means for controlling the action of said spring, substantially as described.

5. The combination of a roll of paper, a feed-wheel, a presser coacting with said wheel to feed the paper from said roll, a spring for ro-

tating said wheel, electromagnetically-operated means for winding said spring, a roll-holder, and a variable escapement mechanism 70 for controlling said holder, substantially as described.

6. The combination of a roll of paper, a feed-wheel, a presser coacting with said wheel to feed the paper from said roll, a spring for 75 actuating said wheel, electromagnetically-operated means for winding said spring, a roll-holder, an escapement for controlling said roll-holder, and a movable stop controlled by the thickness of the roll for varying the throw 80 of a movable member of said escapement, substantially as described.

7. The combination of a roll of paper, a rotatory shaft, feed-wheels on and rotatable independently of said shaft, spring connection 85 between said shaft and said wheels and frictionally connected with at least one of said parts, pressers coacting with said wheels to feed the paper from said roll, electromagnetically-operated means for rotating said shaft 90 to wind said spring connection, a roll-holder, and an escapement mechanism controlling said holder, substantially as described.

8. The combination of an escapement-controlled roll of paper, a rotatory shaft, feed-wheels on and rotatable independently of said shaft, springs connecting said shaft and wheels, each spring being frictionally connected with one of said wheel and shaft elements to slip at a given tension, electromagnetically-operated means for rotating said shaft to wind said springs, and pressers coacting with said wheels to draw the paper from said roll, substantially as described.

9. The combination of a roll of paper, a roll-holder, a variable escapement mechanism controlled from said roll and controlling the rotation of said holder and roll, a rotatory shaft, feed-wheels on and rotatable independently of said shaft, springs for connecting said shaft 110 and wheels and frictionally connected with one of said shaft and wheel elements, electromagnetically-operated means for rotating said shaft to wind said springs, and pressers coacting with said wheels to draw the paper 115 from said roll, substantially as described.

10. The combination of a roll of paper, spring-operated means for unwinding said paper from the roll, a ratchet-wheel connected to and rotating with said roll, a detent and a 120 pawl movable into and out of engagement with said ratchet-wheel, said pawl being mounted to move with said wheel while engaged therewith, and a movable stop controlled in its motion by said roll and variably limiting 125 the throw of said pawl, substantially as described.

11. The combination of a roll of paper, spring-operated means for unwinding the paper from the roll, a ratchet-wheel connected to rotate with said roll, a detent and a pawl 130 movable into and out of engagement with said wheel, said pawl being mounted to move with said wheel while engaged therewith, a mov-

able gravity-operated stop for variably limiting the throw of said pawl, and an arm connected with said stop and resting on the top of said roll to control the motion of said stop, 5 substantially as described.

12. The combination of a roll of paper, spring-operated means for unwinding the paper from the roll, a ratchet-wheel connected to rotate with said roll, a detent and a pawl 10 movable into and out of engagement with said ratchet-wheel, said pawl being mounted to move with said wheel while engaged therewith, a vertically-disposed guideway, a stop moved by gravity and guided by said way, 15 said stop variably limiting the throw of said pawl, and an arm resting on the top of the roll and connected with said stop to control the vertical motion thereof, substantially as described.

20 13. The combination of a roll of paper, spring-operated means for unwinding the paper from the roll, a ratchet-wheel connected to rotate with said roll, a detent and a pawl 25 movable into and out of engagement with said wheel, said pawl being mounted to move with said wheel while engaged therewith, a lever connected with said detent to operate the same, an arm pivotally connected with said lever and provided with a guideway for said 30 pawl, a spring connecting said pawl and arm, and stops for limiting the motion of said arm and pawl, with a returning-spring for said arm, substantially as described.

14. The combination of a roll of paper, 35 spring-operated means for unwinding said paper from the roll, a ratchet-wheel connected to rotate with the roll, a detent and a pawl movable into and out of engagement with said wheel, a lever connected with said detent, an 40 arm pivotally connected with said lever and provided with a guideway for said pawl, a spring connecting said pawl and arm, a fixed stop at one side of said arm for limiting the motion thereof in one direction, a movable 45 stop at the other side of said arm for variably limiting the motion thereof in the other direction, connections between the last-named stop and the roll for controlling the motion of the stop, and a returning-spring for said arm, 50 substantially as described.

15. The combination of a roll of paper, spring-operated means for unwinding the

paper from the roll, a ratchet-wheel connected to rotate with the roll, a detent and a pawl 55 movable into and out of engagement with said ratchet-wheel, a lever connected with said detent, an arm pivotally connected with said lever and provided with a guideway for said pawl, a spring connecting said pawl and arm, a fixed stop at one side of said arm, a gravity- 60 moved stop at the other side of said arm for variably limiting the motion of the arm and pawl, an arm resting on top of said roll and connected with said movable stop to control the motion thereof, and a returning-spring for 65 said pivoted arm, substantially as described.

16. The combination of a roll of paper, a ratchet-wheel rotated thereby, a lever fulcrumed at a point adjacent to the axis of said wheel, an arm extending at an angle to and 70 pivotally connected with said lever and substantially connected with said wheel, a pawl movable on and in the direction of the length of said arm, a spring for said pawl, a detent for said wheel, a connection between the detent 75 and the lever, stops for limiting the motion of said pivoted arm, and means for keeping the strip or web of paper under tension, substantially as described.

17. The combination of a roll of paper, a 80 ratchet-wheel rotated thereby, a lever fulcrumed at a point adjacent to the axis of said wheel, an arm extending at an angle to and pivotally connected with said lever and substantially radial of said ratchet-wheel, a pawl 85 movable on and in the direction of the length of said arm, a spring for said pawl, a detent for said wheel, a connection between said detent and said lever, a fixed stop for said arm, a stop movable in a direction forming an acute 90 angle with said arm and coacting with said arm at variable distances from the pivot thereof, means connected with the roll and controlling the motion of said stop, and means for keeping the strip or web of paper from 95 said roll under tension, and a returning-spring for said arm, substantially as described.

Signed at New York, in the county of New York and State of New York, this 16th day of July, A. D. 1901.

JOHN BURRY.
